UNITED STATES PATENT OFFICE.

ORRIN S. VIGNESS, OF NORTHFIELD, MINNESOTA.

CARBURETER.

1,200,552.

Specification of Letters Patent. Patented Oct. 10, 1916.

Application filed August 28, 1915. Serial No. 47,639.

To all whom it may concern:

Be it known that I, ORRIN S. VIGNESS, a citizen of the United States, residing at Northfield, in the county of Rice and State of Minnesota, have invented new and useful Improvements in Carbureters, of which the following is a specification.

This invention relates to a carbureter for use in connection with internal combustion engines, and particularly to a carbureter designed especially for use in connection with kerosene and like comparatively heavy volatile liquid hydrocarbon fuels, whereby such fuel may be atomized and combined with air and an additional oxygen furnishing agent viz., water, to form a proper fuel mixture.

The primary object of the invention is to provide a carbureter which is sufficient for the stated purpose.

A further object of the invention is to provide a carbureter which is simple of construction, comparatively inexpensive of production, and adapted to regulate the supply of kerosene, air and water in proper proportion according to the weight of the load on the engine, and to vary the admission of the elements of the fuel mixture in definite ratio to each other.

A still further object of the invention is to provide the carbureter by means of which the kerosene, air and water in proper proportions may be combined in an atomized condition with the hydrocarbon to provide an efficient fuel mixture, and which embodies novel and improved means for controlling and regulating the admission of the hydrocarbon and water in definite quantities as required by the engine.

The invention consists of the features of construction, combination and arrangement of parts herein fully described and claimed, reference being had to the accompanying drawings in which:

Figure 1 is a top plan view of a carbureter constructed in accordance with my invention. Fig. 2 is a vertical longitudinal section through the carbureter, showing the valves in closed position.

In carrying my invention into practice, I provide a substantially cylindrical or tubular carbureter body or casing 1, open at one end to provide an air inlet 2 and having its opposite end open to provide a fuel outlet 3, the latter-named end of the casing being formed with a flange 4 for the pas-

sage of bolts to secure the same to the engine manifold.

The supply of air to the carbureter for flow with the fuel agent to the engine is controlled by a valve or damper 5, consisting of a circular disk mounted upon a vertical shaft or stem 6, for oscillation to control the supply of air to the outlet end of the carbureter casing.

The hydrocarbon fuel agent such as kerosene, is supplied to the carbureter through a suitable supply pipe (not shown) which is connected with a nipple 7 communicating with the lower end of a guide tube 8 extending upwardly through a float valve chamber or casing 9. Extending downwardly into this tube 8, which is in communication through slots or perforations 10 with the interior of the float chamber, is a jet tube 75 or nozzle 11, which is supported from the carbureter casing and communicates at its upper end with the latter at a point between the outlet 3 and air valve 5. The upper end of this tube 11 is tapered to form a 80 valve seat adapted to be engaged by the tapered lower end of a fuel controlling valve 12, which works within a threaded opening in the top of the casing 1 and extends outwardly therethrough. A fuel feed 85 or cut-off valve 13 controls communications between the nipple 7 and interior of the float chamber, which latter contains a constant store or supply of the hydrocarbon fuel 14, the stem of the valve 13 being connected with a float 15 in guided connection 90 with the tube 8 and which rises and falls with the level of the liquid 14 to control the supply of hydrocarbon to the float chamber.

A nipple 16, similar to the nipple 7, is provided for connection with a water supply pipe (not shown) leading from a suitable source. This nipple communicates with the lower end of a guide tube 17 disposed within a float chamber 18, and into which depends a jet tube or nozzle 19 supported by and communicating at its upper end with the interior of the carbureter and provided with a tapered seat for engagement with the lower end of a water controlling valve 20 having a threaded engagement with the top of the casing and extending outwardly therethrough. A check valve 21 is provided to control and cut off the feed 105 of water from the source to the chamber 18, which contains a determined quantity of

water 22, and the stem of this valve is connected with a float 23 rising and falling with the level of the water to control the valve 21. The chambers 9 and 18 are provided with air vents 9' and 18', respectively, for an obvious purpose.

In practice, a definite proportion of air is admitted to the carbureter for a mixture with the atomized kerosene, and with this air is entrained a determined amount of moisture, formed by atomized water from the water float compartment, so that a fuel mixture rich in an oxygen furnishing agent will be furnished to support combustion during the entire period of the explosion and consumption of the fuel charge. The portion of the carbureter casing between the outlet 3 and valve 5 constitutes a carbureting chamber 24, in which the elements of the fuel mixture are commingled prior to their admission into the engine cylinder, and in the working of the engine charges of the fuel mixture are drawn at proper intervals into the cylinder by the suction of the piston, the amount of the hydrocarbon and air being controlled in regulated proportions according to the load on the engine, while the supply of moisture is governed automatically by the velocity of the air flowing through the carbureting chamber. The valve 20 accordingly remains open in the operation of the carbureter and is closed only when the carbureter is thrown out of action for any considerable period of time, it being understood that the column of air on its flow through the carbureter produces a partial vacuum of greater or less degree in the tube 19, by which more or less of the water is drawn upward from the chamber 22 and jetted from the tube in an atomized condition, in which condition it passes into the carbureter chamber with the air and combines with the atomized hydrocarbon to form the fuel mixture. It will be understood that the valves 13 and 21 close automatically under the action of the floats when the liquid in each reservoir reaches the predetermined level.

In the normal action of the carbureter the valves 5 and 12 are closed at the beginning of the suction stroke of the piston, and on such stroke a partial vacuum is formed in the chamber 24, and the valves 5 and 12 are opened by their actuating means, whereupon a definite amount of the hydrocarbon, dependent upon the degree of suction and the extent of opening movement of the valve 12, is drawn into said chamber 24 through the tube 11 in an atomized condition, and this atomized hydrocarbon is commingled with the air and moisture also drawn into the chamber 15 by the suction of the piston, the atomized hydrocarbon being thus saturated with air and moisture, so that a fuel charge rich in oxygen furnishing agents, the water

furnishing an added supply of oxygen will be produced, whereby the use of kerosene and other like heavier hydrocarbons may be employed with efficiency.

Connected with the stem of the air valve 70 is a lever or crank member 25, having arms 26 and 27. The arm 26 is designed to be coupled to a suitable operating device whereby said arm may be moved to adjust the valves as desired. Connected with the 75 stem of the valve 12 is a crank arm 28, and pivotally coupled to bolts 29 and 30 carried by the lever arm 27 and the crank arm 28 are divided sections 30' and 31 of a coupling link, which are adjustably connected by a 80 turn buckle 32. The bolt 29 is movable in a longitudinal slot 33 in the lever arm 27 and is carried by a block 34 adjustable along said slot by means of an adjusting screw 35. It will thus be understood that the lever 85 and crank arm are coupled for movement in unison to open the kerosene and air valves together or close them together, and that by means of the turn buckle the 90 length of the link may be varied to change 95 the lead of one of the valves with respect to the other or to adapt them to close at the same time, while by adjusting the bolt 29 along the slot 33 the effective length of the lever arm 27 may be varied to vary the proportion of air, as well as its velocity, to the 100 amount of fuel being supplied, such action also governing the amount of supplied moisture automatically. When the engine is running without load or nearly shut off, the 105 velocity of the air is small, and hence very little or no water is picked up, while when running at full load or wide open the velocity of the air is correspondingly increased, as is also the amount of moisture 110 picked up, this being true also of the kerosene supplied to the carbureting chamber on each suction stroke of the piston. The relative arrangement of the parts described is of importance, in that by placing the moisture supplying means so as to be governed and operated by flowing air the necessity of employing positive controlling devices for this purpose is avoided, while a better atomization of the moisture is effected, and by disposing the air valve at a point between the hydrocarbon and water intakes provision is made for the formation of a vacuum in the chamber 24 and the supply of air and the government of its velocity dependent 115 upon the amount of fuel oil drawn into the carbureter under the action of the engine, whereby maximum efficiency is secured.

I claim:

In a carbureter, the combination of a tubular casing having an air inlet end and a fuel discharge end, an air controlling valve at a point between said ends, water and hydrocarbon supply chambers arranged upon the underside of said tube in respective 120

proximity to the air inlet and fuel discharge ends thereof, said chambers being provided with inlet ports, nozzles communicating with said chambers and extending into the casing, valves upon the casing and controlling said nozzles, slotted tubes within the water and hydrocarbon chambers, floats within said chambers and in guided connection with said tubes, valves controlled by said floats and governing said inlet ports, and means for adjusting the air and hydrocarbon controlling valves in unison.

In testimony whereof I affix my signature in presence of two witnesses.

ORRIN S. VIGNESS.
